DESIGN FOR A VEHICLE

Arno Hecht, Babylon, N. Y., assignor to
Henry Allan Sherwood

Application April 12, 1946, Serial No. 128,505

Term of patent 14 years

(Cl. D34—15)

To all whom it may concern:

Be it known that I, Arno Hecht, a citizen of Germany, residing at Babylon, Long Island, State of New York, have invented a new, original, and ornamental Design for a Vehicle, of which the following is a specification, reference being had to the accompanying drawing, forming part thereof.

The accompanying drawing is a perspective view of a vehicle showing my new design.

The essential features of my design reside in the portions shown in full lines on the drawing.

I claim:

The ornamental design for a vehicle, substantially as shown and described.

ARNO HECHT.
